UNITED STATES PATENT OFFICE

137,558

DESIGN FOR A SKIRT

Helene Pons, New York, N. Y.

Application July 10, 1943, Serial No. 110,650

Term of patent 3½ years

(Cl. D3—26)

To all whom it may concern:

Be it known that I, Helene Pons, a citizen of the United States, residing at New York city, in the county and State of New York, have invented a new, original, and ornamental Design for a Skirt, of which the following is a specification, reference being had to the accompanying drawing, forming a part thereof.

Fig. 1 is a front view of a skirt, showing my new design, as it would appear on the wearer.

Fig. 2 is a rear view of the skirt shown in Fig. 1.
Fig. 3 is a front view of the skirt shown in Fig. 1, but in open or extended position.

I claim:

The ornamental design for a skirt, substantially as shown.

HELENE PONS.
